(57) **CLAIM**

I claim the ornamental design of a outer connector, as shown and described.

DESCRIPTION

FIG. 1 is a front, top perspective view of an our connector showing an embodiment of my new design;

FIG. 2 is a front, bottom perspective view of the our connector of FIG. 1;

FIG. 3 is a front elevated view of the our connector of FIG. 1;

FIG. 4 is a rear elevated view of the our connector of FIG. 1;

FIG. 5 is a left-side elevated view of the our connector of FIG. 1;

FIG. 6 is a right-side elevated view of the our connector of FIG. 1;

FIG. 7 is a top plan view of the our connector of FIG. 1;

FIG. 8 is a bottom plan view of the our connector of FIG. 1; and,

FIG. 9 is a cross section view of the our connector of FIG. 7 along line 9-9.

The broken lines consisting of dashes show an environment that forms no part of the claimed design.
